UNITED STATES PATENT OFFICE.

JOHN W. SHEAFFER, OF FRANKLIN, YORK COUNTY, PA.

CAR-COUPING.

SPECIFICATION forming part of Letters Patent No. 288,502, dated November 13, 1883.

Application filed April 2, 1883. (No model.)

To all whom it may concern:

Be it known that I, JOHN WESLEY SHEAFFER, of Franklin township, York county, State of Pennsylvania, have invented a new and Improved Car-Coupling; and I hereby declare the following to be a full, clear, and exact description thereof, reference being had to the accompanying drawings, making part of this specification, in which—

10 Figure 1 is a perspective view of the coupling approaching the coupling-point. Fig. 2 is a plan view with the tops of the draw-heads removed. Figs. 3 and 4 are details to be referred to.

15 My invention consists of sundry details of construction, as hereinafter described, and specifically pointed out in the claims.

In order that those skilled in the art may make and use my invention, I will proceed to 20 describe the manner in which I have carried it out.

In the said drawings, A A are the draw-heads, and B B the coupling devices. These coupling devices or rods are made with barbed heads b and square bases d, the barbed ends 25 catching over the square bases and sustained against any side throw tending to disengage them, by means of stout springs C C, which bear against the curved back of the barbed heads. The coupling-rods B B are pivoted at 30 e e by coupling-pins f f, and their contiguous faces are made in opposite curves, g g' and h h', joined by diagonal sections i i'. Sliding blocks D D, resting on the bottoms of the draw-heads, and moved transversely by means

of levers E, pivoted to any convenient point of the platform, serves to disengage the coupling-rods by their heads l l forcing the barbed ends against springs C C, and out of contact with the square bases d d. In addition to the 40 holes for pins f f, the draw-heads are supplied with the ordinary holes when the common coupling-link is used, so that when a car provided with my improved coupling has to couple with a car having the ordinary pin and link, pin f can be at once removed, rod B taken out, and the pin transferred to hole for that purpose, and the ordinary link-coupling used. As the cars approach their momentum forces the barbed heads by springs C to the 45 coupling-position. When the barbed points are disengaged and the cars recede, the convoluted faces strike against each other, and prevent the barbed heads catching each other.

Having thus described my invention, what I claim as new, and desire to secure by Letters Patent, is—

1. The draw-heads A A, in combination with the convoluted coupling devices B B, substantially as described. 55
2. In a car-coupling, the coupling devices B B, engaging each other by means of heads b b, in combination with the transverse sliding bars D D, having heads l l, the springs C C, and levers E E, operating as described, as 60 and for the purpose set forth.

JOHN WESLEY SHEAFFER.
